POSITION SELECTOR

Joseph A. Ramos, San Francisco, Calif.

Application March 25, 1938, Serial No. 198,038

11 Claims. (Cl. 172—239)

My invention relates to position selectors, and more particularly to such a device which can be used for selective step tuning of radio circuits, such as, for example, radio receivers.

5 This application is a continuation in part of my prior application entitled "Position selector," Serial No. 172,228, filed November 1, 1937.

Among the objects of my invention are: To provide a step by step position selector wherein a 10 360° contact arc is provided with a 180° arc of rotation; to provide a means and method of utilizing a 360° contact arc with a 180° shaft rotation in a position selector; to provide a means and method of utilizing a position selector to include an on and off switch; to provide a position 15 selector utilizing remote control; to provide a position selector utilizing a reversing motor; to provide a simple, accurate and fast position selector, ideally adapted for use in radio receivers; and to provide a position selector embodying a band shift.

20 My invention possesses numerous other objects and features of advantage, some of which, together with the foregoing, will be set forth in 25 the following description of specific apparatus embodying and utilizing my novel method. It is therefore to be understood that my method is applicable to other apparatus, and that I do not limit myself, in any way, to the apparatus of the 30 present application, as I may adopt various other apparatus embodiments, utilizing the method, within the scope of the appended claims.

Referring to the drawings:

Fig. 1 is a top plan view, partially diagrammatic, showing the relationship of the position selector of my invention to the remainder of a 35 radio receiving set.

Fig. 2 is a longitudinal sectional view of one 40 preferred form of my invention, taken as indicated by the line 2—2 in Fig. 1.

Fig. 3 is a plan view of the rotating disc, taken as indicated by the line 3—3 in Fig. 2.

Fig. 4 is a front view of the position selector, 45 showing the push button arrangement and indicating hand.

Fig. 5 is a detailed sectional view of a push button assembly, as utilized in the device of Fig. 2.

50 Fig. 6 is a schematic wiring diagram of the devices shown in Figs. 1 to 5 inclusive.

Fig. 7 is a view, partly in section and partly in elevation, of a modification of my invention, as used for remote control.

55 Fig. 8 is a schematic wiring diagram applied

to the device of Fig. 7, showing one circuit for operation thereof.

Fig. 9 is a detailed, partially sectional view of a portion of the mechanism shown in Fig. 7.

Fig. 10 is a circuit diagram illustrating an 5 electrical position lock.

Fig. 11 is a partial view showing locking position.

In my prior application cited above, I laid down the fundamental principles of a position 10 selector utilizing push buttons in conjunction with a reversing motor, wherein a divided conductor was used, the motor locking when the push button contact made electrical connection to both sectors of the divided conductor. The present 15 invention is a modification and improvement on the former device, in that it provides for 360° location of the push buttons, with only 180° rotation of the operating shaft. My present invention also provides for remote control with 20 the same 360° spacing of station selector contacts.

My invention, however, may be more fully understood by direct reference to the drawings, 25 wherein all devices show a lesser number of push buttons or equivalent contacts than might be used in actual practice. A larger number in the drawings would be mere duplication, and it is therefore only necessary to show a sufficient number to demonstrate the operability of the device. 30

The essential features of my invention comprise a tuning motor 1, a selecting assembly 2, and a tuning condenser 3. This assembly may be applied to any radio set, schematically represented by chassis 4 in Fig. 1.

Tuning condenser 3 is provided with an extended shaft 5 on which is mounted a worm gear 6 meshing with a worm 7, driven through flexible shaft 8 by motor 1. Assembly case 9 is stabilized in any convenient manner, and contains a rotating disc 10 on which is mounted a continuous ring 11 and a split ring divided into right ring section 14 and left ring sector 12. Insulator 13 keeps these members electrically separate. 45 The ends of these sectors abut but do not touch, and I prefer to provide notches 15 in one corner of each sector at its end, adjacent notches cooperating with a ring notch 16, to form a contact receptacle. 50

Ring sectors 12 and 14 are spaced slightly from continuous ring 11 to provide a narrow channel 17 aligned with the contact receptacles. Case 9 is provided with a front face 19, preferably of insulating material, and shaft 5 is extended 55

through this front face to carry an indicating hand 20 operating over a station chart 21.

Immediately outside of the arc of rotation of indicator 20 are positioned a series of push button assemblies 22, spaced around 360°. These push button assemblies are shown in detail in Fig. 5. The inner end of each push button assembly is provided with a contact point 25 positioned just above channel 17, and of a size to readily fit in notches 15, but small enough to clear ring notch 16.

Contact 25 bears against the inner wall of sliding sleeve 26, the opposite end being closed by cone 27. Contact 25 is held within sleeve 26 by shoulder 29, and is held thereagainst by contact spring 30. Sleeve 25 is movable in push button frame 31 and restrained by sleeve spring 33. The frames 31 are mounted in conductive sector 32 in a slot 34. The conductive sectors 32 are slightly less than half circles, and electrically separate. Push button frames 31 are movable in slot 34 if forced against the friction developed by push button frame spring 36, the tension of this spring being adjusted by spring nut 37. Thus, within reasonable limits, the arcuate positions of each push button assembly may be adjusted in slot 34.

Each push button assembly 22 is operated by push button 40 extending through the front face 19, and push button 40, at the rear, is provided with a planar operating surface 41 of greater extent than cone 27, so that irrespective of minor variations in position of cone 27, the assembly will still be operative upon pressure exerted on push button 40.

In utilizing this type of device, I prefer to use a circuit such as shown in Fig. 6. Here, an induction motor is preferably utilized, although any reversing motor having double reversing windings may be employed.

In the form of motor shown, the main field is provided by a continuous winding 50 on the middle of core 52, one end of the winding being attached to one leg 51 of the main supply, and the other end being attached to common wire 54. Over field winding 50 is wound an additional field winding 55 having a center tap 56 attached to common wire 54, the opposite ends 57 and 58 of this winding being attached to sectors 32 bearing the push button assemblies. Common wire 54 also connects to center tap 59 of a double crescent winding 60, wound around one side of split poles 61. The ends of the crescent winding are connected to sector rings 12 and 14 respectively. Continuous ring 11 is connected to the other leg 62 of the main supply.

In operation, any one of the buttons 40 may be pushed. Pressure is applied against cone 27, which forces barrel 26 toward disc 10. Contact 25 will thereupon approach channel 17 and make contact simultaneously with continuous ring 11 and one or the other of sectors 12 or 14. The motor will thereupon be energized in one direction, and the shaft will rotate until a ring notch 16 is reached. The normal distance between contact 25 and the rotating rings is less than the permissible travel of barrel 26, so that spring 30 is slightly compressed and contact 25 is away from shoulder 29. However, when contact 25 reaches a point just above adjacent notches 15 the motor will stop, due to the fact that at this point no contact will be made to ring 11 due to clearance of notch 16, and mechanical latch 13' will center the disc. Pressure is then withdrawn from push button 40, contact 25 withdraws from notches 15 and latch 13' due to the urge of the

push button assembly return spring, and the attached tuning condenser 3 remains in the selected position.

Upon operation of any other push button, the same operation occurs. Each time the disc 10 will stop in the proper location, and with a different amount of tuning condenser surfaces in capacitative engagement. The exact tuning for each station is accomplished by moving each push button assembly arcuately against the restraint of position springs 36.

It will be noted, however, that I have provided for 360° positioning of the push buttons by utilizing two 180° sectors 32. If a button in the upper sector is pushed, the motor will start in one direction, in accordance with the contact with ring sectors 12 or 14. However, when the buttons in the lower sector 32 are pushed, the start of the motor is reversed due to the reversal of current through the divided field winding. Thus, the same scale can be used on arrow 20 for both upper and lower sectors, and furthermore, the indicator 20 will always come up to the button and stop. Thus, it will be seen that I utilize a double reversing motor, reversing in one instance to select a station, and reversing in the other instance to allow the positioning of buttons on the opposite 180° arc.

It will be noted that by the use of the continuous ring 11 in conjunction with ring sectors 12 and 14, that no current is utilized in the motor except when it is rotating. Furthermore, it should be noted that reliance is not placed upon a mechanical stop to stop the motor, and thus there are no inertia shocks against contact 25. The motor stops instantly, due to the fact that supply current to the motor is completely broken.

In Figs. 7 and 8 I have shown a remotely controlled modification of my invention, also utilizing 360° distribution of selector contacts. The important portion of the actuating mechanism is shown in Fig. 7. Here, disc 10 carries only ring sectors 12 and 14. Contact 25 is contained in a contact assembly 70, and is permanently forced against one or the other of sectors 12 or 14. Each contact assembly is electrically separated and mounted in a contact holder 71, of insulating material. Each contact assembly 70 is also provided with an intermediate contact 72 on the other side of assembly 70, and this is permanently forced against one of a ring of electrically separated intermediate contact discs 74, each one being provided with a wiring lug 75.

Contact discs 74 are carried by a supporting disc 76 mounted on shaft 5 and free to rotate thereon. The motion of supporting disc 76 is controlled by driving arm 77 having a driving pin 79 thereon, rotating in slot 80 in disc 76, this slot being slightly less than 180° in arc. Thus, at either end of a 180° rotation of shaft 5, disc 76 will be oscillated over a narrow angle, and only at the end of the travel, as determined by the position of pin 79.

The oscillation of disc 76 is also used to control a reversing switch comprising an insulated arm 82, pivoted on pin 83, and engaging in operating notch 84 on the periphery of disc 76. The other end of arm 82 is provided with a switch arm 85 making selective contact with reversing connections 86 of the crescent windings 60 of the motor, as will be explained later.

I also prefer to position on shaft 5 a main switch operating arm 88, which at one end of its 180° travel, hits an operating extension 89 of main switch 90 to separate contacts 91 thereof.

and thus remove all current from the device, as will be explained later.

When contact 25 reaches the junction of sectors 12 and 14, notches 15 are made large enough to clear contact 25, and I may desire to allow contact 25 to fall into a positioning depression 93 in insulator 13.

Referring directly to Fig. 8 for the operation of the circuit, it will be seen that the motor utilized is identical with the motor described in conjunction with Fig. 6. Contact discs 74, in the upper 180° of disc 76, are connected through wires 92 to similar contacts in the lower 180°. However, the contact discs in the lower 180° are staggered in relation to those in the upper 180°, so that when disc 76 is rotated by pin 79 to one position, the intermediate contacts 72 are in electrical connection with the contact discs 74 in the upper 180° of disc 76, and when disc 76 is rotated to its other position, the electrical connections in the upper 180° are broken, and made in the lower 180°. Thus, the contact discs 74, over the entire 360° circle on supporting disc 76, may be utilized to make connection to selected positions within the 180° range of rotation of disc 10.

Connecting lugs 75, over one-half only of contact discs 74 on one 180° arc, are connected in order to operating wires 100, each one running to the middle stationary contacts 104 of a series 30 of aligned push buttons, each having three stationary contacts. Left hand contacts 102 are all connected together, and connect to one side 104 of the main power transformer 105. Right hand contacts 106 of each push button assembly 35 are all connected together and lead through wire 107 to switch arm 85, controlling the reversal of field windings 55. Contacts 91 are in series with the primary of power transformer 105. Thus, when arm 89 contacts operating arm 89, no power 40 can flow in the radio set.

Left hand push button 110 runs to special contacts 111. These are closely adjacent, and one on each side of the dividing line of the 180° segments. These cause the set to be turned off, inasmuch as they will rotate arm 88 against operating arm 89 of main switch 90 to open the circuit thereof. The next adjacent button 112 is the band shift button, causing a complete 180° rotation of shaft 5, thus shifting the position of disc 50 76. Each of the other push buttons, therefore, will represent two separate stations, depending upon the position of disc 76.

The connection of the remainder of the radio set is purely conventional. Power transformer 55 105 is provided with a filament cathode 120 feeding the tubes of the radio set as exemplified by final power tube 121. Output of this power tube passes through output transformer 122 and thence to output speaker 123.

In order, however, that tuning may be accomplished from a position remote from speaker 123, I utilize speaker 124 to carry output modulation, by connecting to the operating portion thereof an output line 125, the speaker 124 being located at the remote point from which tuning is done. This speaker may be provided with the usual volume control 126 and tone control 127.

Fig. 10 shows a slight modification of my invention whereby electrical locking is obtained in the final position and this modification of my invention utilizes a slightly different motor than that shown in Fig. 6. In this modification coils equivalent to crescent coils 69 are wound upon separate legs 140 of a central pole piece 141, whereas both the main field winding 50 and the

reversing winding 55 are wound around the main leg 141. Under these circumstances, therefore, in the modification shown in Fig. 6 when the contact 25 reaches the desired position, it breaks contact with continuous ring 11 and remains in 5 contact with ring sectors 12 and 14. In the modification shown in Fig. 10, however, the contacts are made as shown in Fig. 11, and in this modification contact point 25 breaks all connection with both ring sectors 12 and 14 but remains 10 in contact with continuous ring 11 in ring notch 16, which in this case is made small enough to accommodate contact point 25 in electrical contact therewith. Under these conditions it will be seen that current is removed entirely from both 15 of the windings 55 equivalent to the crescents and that, therefore, not only does all tendency toward rotation immediately cease because of the equal magnetism of legs 140, but also complete locking of the armature 1 will take place. Thus 20 in this modification mechanical locking is not relied upon, inasmuch as electrical locking will take place just as soon as contact point 25 leaves either ring sector 12 or 14 but remains in contact with continuous ring contact 11. 25

It will thus be seen that I have provided a remote control device wherein complete control may be had of a radio set at a distance, wherein the radio set may be turned on and off, and wherein twice the number of stations may be obtained 30 than there need be push buttons therefor. Furthermore, I have provided a circuit whereby the action of the remote tuning device may be monitored.

I claim:

1. In combination with an electric motor selectively rotatable in either direction by selective closure of two substantially balanced circuits common to said motor, a position selector comprising a shaft to be rotated, a conductor moved 40 in synchronism with said shaft over a predetermined path, said conductor being divided into two electrically separate divisions with adjacent ends, a connection between each of said divisions to a separate one of said circuits, a second and un- 45 divided conductor extending adjacent and parallel to said first divided conductor, a plurality of conductive means manually controlled to contact said divided conductor and said undivided conductor simultaneously, a power connection to said 50 undivided conductor, said undivided conductor being notched at the junction of said adjacent ends to clear said conductive means, at that point thereby stopping said motor and a common connection to said conductive means completing the 55 motor circuit.

2. Apparatus in accordance with claim 1 wherein in said plurality of conductive means are divided into two groups each group completing the motor circuit through a separate and auxiliary reversing 60 winding on said motor.

3. Apparatus in accordance with claim 1 wherein in said plurality of conductive means are divided into two groups each group completing the motor circuit through a separate and auxiliary reversing 65 winding on said motor, said divided and undivided conductors being circular in shape and wherein the groups of conductive means are in separate 180° arcs.

4. In combination with an electric motor se- 70 lectively rotatable in either direction by selective closure of two substantially balanced circuits common to said motor, a position selector comprising a shaft to be rotated, a conductor moved in synchronism with said shaft over a 75

- predetermined path, said conductor being divided into two electrically separate divisions with adjacent ends, a connection between each of said divisions to a separate one of said circuits, said 5 electrically separate divisions forming a circle, a contact disc free to move on said shaft and having line contacts thereon spaced around 360°, the contacts on one 180° sector being staggered with respect to those on the other 180° sector 10 and connected together in their respective positions, a plurality of intermediate contacts spaced around said circle and bearing on said electrically separate divisions and on one 180° group of line contacts, means mounted on said shaft, shifting said contact disc by an amount sufficient to 15 shift connection of the one 180° group of line contacts to the other, a plurality of lines leading from said line contacts, a plurality of switches manually operable to energize said motor through 20 said line contacts and said electrically separate divisions, and additional means for reversing the connections of said motor whenever said contact disc is shifted.
5. Apparatus as recited in claim 4 wherein circuit breaking means is operated when said contact disc is shifted in one direction to de-energize said position selector.
6. In a position selecting device, a shaft, a motor having a rotor connected to rotate said 30 shaft over 180° only, said motor having two separate sets of reversing windings, contact means spread over 360° for automatically starting and stopping said motor, said contact means being divided into 180° groups both groups being connected to one set of reversing windings in accordance with the arcuate position of the contact means, each of the contact means in each 35 180° group being connected to an end of the other reversing winding.
- 40 7. In combination with an electric motor selectively rotatable in either direction by selective closure of two substantially balanced circuits common to said motor, a position selector comprising a shaft to be rotated, a conductor moved in synchronism with said shaft over a predetermined path, said conductor being divided into two electrically separate divisions with adjacent ends, a connection between each of said divisions to a separate one of said circuits, a second and undivided conductor extending adjacent and parallel to said first divided conductor, a plurality of conducting means manually movable to contact said divided conductor and said undivided conductor simultaneously, a power connection to 45 said undivided conductor, said adjacent ends being notched to clear said conductive means while said conductive means is still in contact with said undivided conductor.

8. Apparatus in accordance with claim 7

wherein said motor is provided with windings connected to said divided conductor causing rotation, and wherein removal of current from both of said windings will cause said motor to lock.

9. Apparatus in accordance with claim 7 5 wherein said motor is provided with means causing motor lock when said conductive means clears said adjacent ends.

10. In combination with an electric motor selectively rotatable in either direction by selective closure of two substantially balanced circuits common to said motor, a position selector comprising a shaft to be rotated, a circular conductor moving in synchronism with said shaft over a predetermined path, said conductor being divided into two electrically separate substantially semicircular divisions having adjacent ends, a plurality of contact means engageable with either division of said conductor, said contact means being divided into semi-circular groups, a connection between each of said divisions with a respective one of said balanced circuits, whereby connection to the two divisions respectively will cause opposite rotation of said motor, a power supply circuit, means for completing a circuit 25 from said power supply circuit to said motor through a selected one of said contact means, and connections between the respective groups of contact means and said motor whereby energization of individual members of said respective groups will cause said motor to rotate in opposite directions with respect to the division of said conductor energized thereby.

11. In combination with an electric motor selectively rotatable in either direction by selective closure of two substantially balanced circuits common to said motor, a position selector comprising a shaft to be rotated, a circular conductor moving in synchronism with said shaft over a predetermined path, said conductor being 40 divided into two electrically separate substantially semicircular divisions having adjacent ends, a plurality of contact means engageable with either division of said conductor, said contact means being divided into semicircular groups, a connection between each of said divisions with a respective one of said balanced circuits, whereby connection to the two divisions respectively will cause opposite rotation of said motor, a power supply circuit, means for completing a circuit 45 from said power supply circuit to said motor through a selected one of said contact means, and means for connecting the respective groups to said motor so that energization of individual members of said respective groups will cause opposite rotation of said motor when contacting the same division of said circular conductor.

JOSEPH A. RAMOS.
